UNITED STATES PATENT OFFICE.

JOHN D. MCINTYRE, OF EVERETT, MASSACHUSETTS.

DEVICE FOR SOAKING CORKS.

1,126,239.

Specification of Letters Patent.

Patented Jan. 26, 1915.

Application filed April 25, 1914. Serial No. 834,542.

To all whom it may concern:

Be it known that I, JOHN D. MCINTYRE, a citizen of the United States, and resident of Everett, in the county of Middlesex and 5 State of Massachusetts, have invented new and useful Improvements in Devices for Soaking Corks, of which the following is a specification.

This invention relates to devices for soaking corks preparatory to the bottling of certain liquids such as wines and liquors.

In order to render corks sufficiently soft and elastic to be properly compressed into the mouth of a bottle and to make and hold 15 a light seal, it is the practice to soak them in water; and heretofore, as far as I am aware, this has been done in an open tub or pail of water. The corks however are so light that they float high out of the water, 20 and if a considerable mass of corks is put in the tub together many of them would never reach the water at all if they were not pushed down by the user by hand. Such momentary and intermittent immersions are 25 quite unsatisfactory and insufficient to give the corks the thorough soaking and saturation, which they require to bring them to the best condition. Furthermore, if the bottler, as is usual, immerses the mass of corks with 30 his hand, each time he picks one up to put it in a bottle, the cork is taken from the tub dripping from the surface, though possibly drying the interior, and the water deteriorates the contents of the bottle to a greater 35 or less extent.

With my invention the corks will be thoroughly soaked and saturated, without plunging them under water by hand in the present fashion, and will also be presented 40 for use in soaked condition, but substantially free of surface drippings.

In the accompanying drawings which illustrate one embodiment of the invention,—Figure 1 is a longitudinal central section of 45 a cork soaking device containing my invention; Fig. 2 is a plan view of said device; and Fig. 3 is a sectional detail of the latch for the lid, hereinafter described.

A is an open top vessel, preferably having 50 vertical cylindrical side walls. Said vessel

may be made of sheet metal such as galvanized iron, or other suitable material. On the inner wall of the vessel A are a plurality of tiers or courses of supporting projections B, consisting as herein shown of short strips 55 of metal arranged vertically, and secured to the walls of the vessel A by rivets b, or by soldering.

C represents a removable screen or dia- phragm, which extends transversely of the 60 vessel, and is adapted to hold the corks sub- merged when the vessel is filled with water up to or above the level of the screen. The screen C rests upon and is supported by any of the several tiers or supports B, so that 65 the height of the screen in the vessel may be varied. Said supports are so arranged as to hold the screen above the bottom and below the top of the vessel, so that there will be space below the screen for a mass of corks, 70 while the vessel may be filled with water at least to the top of the screen, without over- flowing.

The screen C is preferably of frusto-coni- cal form, and may be of sheet metal, wire 75 fabric, or other suitable material to hold a mass of corks submerged. As herein shown it is of sheet metal and comprises inclined or conical side walls c', and a marginal flange c, which rests on the supports B. 80 The flange c is provided with notches c² spaced to correspond with the supports B, which pass through the notches c² when the screen is turned to bring the notches into register with the supports B, thus permitting 85 the screen to be lowered to any desired tier of supports. The supports of the sev- eral tiers are preferably arranged in offset or staggered relation, as shown, and each tier acts as a lock, when the screen has been 90 lowered to the next tier below, to hold the screen against upward movement under the buoying influence of the corks, which might otherwise float the screen upward if their bulk were sufficient to sustain the weight of 95 the screen. The screen C may be provided with handles D for convenience in manipu- lating it.

A central aperture is provided at the top of the screen, of relatively small diameter, 100

to which is hinged a lid E, also provided with a handle e, and normally held closed by a latch or spring catch F. Holes c' are formed in the conical walls c' to permit the 5 free passage of water therethrough, but too small to permit the passage of a cork.

In operation the corks are placed in the vessel, and the screen C inserted at the desired height according to the quantity of 10 corks to be treated and the volume of water which it is desired to use. Even with a small number of corks the screen may be supported on one of the higher tiers of supports B and water filled in to the top of the 15 screen; but one of the advantages of having the screen adjustable is to enable a small volume of water to be used for a small number of corks,—a consideration which may be of importance when the water has to be 20 carried by hand or when hot water is used and the supply is limited. After the corks have been kept submerged a sufficient length of time to be ready for use, the lid E is opened, and the corks, tending to rise through the 25 small central aperture, become jammed at the opening, permitting a few at the top to be forced clear of the water and presented for use soaked, but well drained, while the mass is held under water. As the corks are 30 used one by one from the top of the jam, others from below gradually work their way up. After enough corks have been removed materially to lower the water level, so that any considerable portion of the mass floats 35 out of water, the screen may be adjusted downward to rest on the next lower tier of supports B, thereby keeping the mass submerged.

The under surface of the frusto-conical 40 screen C, which is inclined upwardly from the periphery or margin of the screen toward the central aperture, guides and directs the buoyant corks toward the aperture, and prevents any of them from becoming 45 entrapped or caught at the side of the aperture, as would happen if the screen were flat. Moreover, the similarly inclined upper surface of the screen forms with the walls of the vessel an annular trough which 50 admits an annular body of water above the screen and around the aperture when the vessel is filled with water up to the level of the top of the screen, so that if any cork or corks are pushed up through the aperture 55 and fall to one side they will fall into the surrounding annular body of water on top of the screen and be kept wet.

I claim:

1. A device for soaking corks, comprising 60 an open top vessel, a transverse screen within said vessel, adapted to hold the corks submerged when the vessel is filled with water up to or above the level of the screen, and means fixed to the inner side of the

walls of said vessel to support said screen 65 above the bottom and below the top of the vessel.

2. A device for soaking corks, comprising an open top vessel, a transverse screen within said vessel having an aperture therein, the 70 under surface of which screen inclines upwardly from its periphery toward said aperture, adapted when the vessel is filled with water up to or above the level of the screen to hold the corks submerged and to guide 75 them toward said aperture, and means to support said screen above the bottom and below the top of the vessel.

3. A device for soaking corks, comprising an open top vessel, a transverse screen 80 within said vessel having an aperture therein, a cover for said aperture, both the under and the upper surfaces of said screen inclining upwardly from the periphery of the screen toward said aperture, adapted when 85 the vessel is filled with water up to the level of the top of the screen to hold the corks submerged, to guide the corks toward said aperture, and to admit an annular body of water above the screen around said aperture, 90 and means to support said screen above the bottom and below the top of the vessel.

4. A device for soaking corks, comprising an open top vessel, a transverse screen within said vessel, adapted to hold the corks 95 submerged when the vessel is filled with water up to or above the level of the screen, said screen having an aperture therethrough, a lid for closing said aperture, and means fixed to the inner side of the walls of said 100 vessel to support said screen above the bottom and below the top of the vessel.

5. A device for soaking corks, comprising an open top vessel, a transverse screen within said vessel, adapted to hold the corks 105 submerged when the vessel is filled with water up to or above the level of the screen, and means fixed to the inner side of the walls of said vessel to support said screen at varying heights above the bottom and be- 110 low the top of the vessel.

6. A device for soaking corks, comprising an open top vessel, a transverse screen within said vessel adapted to hold the corks 115 submerged when the vessel is filled with water up to or above the level of the screen, a number of tiers of projections fixed to the inner side of the walls of said vessel to support said screen at varying heights above the bottom and below the top of the vessel, and 120 each tier of projections being adapted to lock the screen against upward movement under the buoying influence of the corks, when the screen rests on the next lower tier.

7. A device for soaking corks, comprising 125 an open top vessel having cylindrical side walls, a plurality of tiers or courses of screen supporting projections secured within the

cylindrical walls of the vessel at different heights, and a screen removably held in said vessel adapted to rest upon said supporting projections, said screen having marginal notches through which said projections will

5 pass whereby the screen may be supported on any of said tiers of projections.

Signed by me at Boston, Massachusetts, this 22d day of April 1914.

JOHN D. McINTYRE.
